(57) **CLAIM**

The ornamental design for a display screen or portion thereof with animated graphical user interface, as shown and described.

DESCRIPTION

FIG. 1 is a front view of a display screen or portion thereof with animated graphical user interface showing a first image of the claimed design;

FIG. 2 is a second image thereof;

FIG. 3 is a third image thereof;

FIG. 4 is a fourth image thereof;

FIG. 5 is a fifth image thereof; and,

FIG. 6 is a sixth image thereof.

The outermost broken lines in the figures show a display screen or portion thereof and form no part of the claimed design. The other broken lines in the figures show portions of the animated graphical user interface that form no part of the claimed design.

The appearance of the animated image transitions between the images shown in FIGS. 1-6. The process or period in which one image transitions to another forms no part of the claimed design.

The Lorem Ipsum text is exemplary of content and is used to show the appearance of effects on it. The claimed design is not intended to be limited to the Lorem Ipsum text shown. Other user-defined text and/or content is contemplated by the inventors.
